Des. 229,572

Patented Dec. 11, 1973

229,572

TOY DOG

Betty Jo Gonzalez, 5426 S. Wolcott, Chicago, Ill. 60609

Filed Sept. 14, 1971, Ser. No. 180,535

Term of patent 14 years

Int. Cl. D21—01

U.S. Cl. D34—2 R

FIG. 1

FIG. 2

FIG. 3

FIG. 4

FIG. 5

FIG. 6

FIG. 7

FIG. 1 is a perspective view of toy dog embodying my new design;

FIG. 2 is an enlarged perspective view of the face of the dog;

FIG. 3 is a side elevational view, taken from the left side of FIG. 1, the view of the dog from the right side of FIG. 1 corresponding to that of the left side;

FIG. 4 is a front elevational view;

FIG. 5 is a rear elevational view;

FIG. 6 is a top plan view;

FIG. 7 is a bottom plan view.

I claim:

The ornamental design for a toy dog, as shown.
